UNITED STATES PATENT OFFICE

CHARLES W. WOOD, OF LONDON, ENGLAND, ASSIGNOR TO GENERAL ELECTRIC COMPANY, A CORPORATION OF NEW YORK

ELECTRIC SWITCH

Application filed March 7, 1925, Serial No. 13,867, and in Great Britain March 14, 1924.

My invention relates to electric switches, particularly to high tension switches and an object of my invention is the provision of improved means for preventing a person from obtaining access to the live elements of such a switch without first actuating another switch to render dead the circuit of the first switch.

In accordance with the embodiment of my invention disclosed herein I employ one or more oil switches which are enclosed in chambers having doors which are adapted to be locked closed by means of a key. In circuit with the oil switch is an isolating switch and a lock actuated by the same key is provided for locking it in open circuit position. The key cannot be removed from the lock of the isolating switch without first moving this switch to open circuit position and locking it in that position after which the key may be applied to the lock controlling the oil switch chamber. This latter lock, moreover, is so constructed that the key is retained therein as long as the door remains open to any extent so that it cannot be removed while the door is open and be applied to the isolating switch lock.

My invention will be better understood from the following description taken in connection with the accompanying drawing, and its scope will be pointed out in the appended claims.

Figure 1 shows a part of the mechanism involving my invention for operating an isolating switch having a key controlled lock attached thereto; Fig. 2 is a detail thereof; Fig. 3 is a top view of a sliding chamber door having a lock adapted to receive the key fitting the isolating switch lock; Fig. 4 is a view of the door taken on the line 4-4 of Fig. 3; Figs. 5 and 6 are views similar to Figs. 3 and 4 respectively, showing a modification; Fig. 7 shows a further modification; Figs. 8 and 9 show details of Fig. 7 and Fig. 10 is a diagrammatic representation.

In Fig. 10 I have illustrated in a diagrammatic manner only an isolating switch 4 and an oil switch 5 connected in series to a line 6. It is to be understood that these switches may be of any well known form and that a second

isolating switch may be arranged on the other side of the oil switch if desired. By way of example I have shown the isolating switch as operated through a crank 7 and a link 8. While the operating mechanism of the oil switch is not shown, a tripping means therefor is shown diagrammatically comprising a rod 9 engaging a notch 10 in the movable contact. Referring now to Figs. 1 and 2 the link 8 is pivotally connected to the arm 11 of the hub 12 which is mounted for rotation on the shaft 13 carried by brackets 14. The brackets 14 are secured to the base 15 by bolts 16, and the whole may be fixed in any convenient place relative to the switch-gear for instance, on a fixed part of the frame thereof. The hub 12 is provided with an opening 17 adapted to accommodate the end of an operating implement when it is desired to operate the isolating switch. To ensure that the isolating switch shall not be opened until the circuit-breaker with which it is associated has first been tripped, a shutter 18, operable by a handle 19, is mounted on the disc 22 for rotation about the shaft 13 and is arranged normally to cover, or partly to cover, the opening of the hole 17. Operatively connected to the disc 22 and thereby to the shutter 18 is a link 21, the other end of which is arranged to effect the tripping of the circuit-breaker in any suitable way when the link is actuated by rotation of the shutter 18 to a predetermined position. On the disc 22 are secured stop-pins 23. Fixed with respect to the base 15 is a bracket 24 to which are pivoted a pair of links 25 suitably shaped on their adjacent sides to rest against a sleeve 26 on the shaft 13 and also to bear against the stop-pins 23. The links 25 are biased towards each other by means of a spring 27. With this arrangement, when the shutter 18 is rotated clockwise, (Figs. 1, 2) the disc 22 is rotated and therewith the stop-pins 23, the upper one of which moves along the curve indicated by the broken line 28 against the curved portion of the upper link 25, thus forcing it out into the position shown by broken lines against the biasing effect of spring 27. In this position there is a tendency for the shutter to be forced back into its normal po-

sition under the influence of the spring 27. A spring-controlled clamping device, having an arm 29 pivoted at 30 and adapted to engage with a cooperating catch or catches (not shown) on the disc 22 is provided for latching the shutter in an operated position, for example, when it has been rotated clear of the opening of hole 17. Pressure on the control surface 31 of the clamping device effects the release of the shutter.

Mounted on the bracket 33 secured to the bracket 14 by bolts 34 is a lock 35 adapted to accommodate a key 36. The key and the lock are of any well-known construction but are arranged so that the key is insertable in or withdrawable from the lock only when the locking lever thereof is in a predetermined position, that is, locked. Such an arrangement might be obtained, for example with any keyhole lock provided that the rotation of the key in the lock were limited to an angle of less than 360° . Operable by the moving element of the lock is a shaft 37 to which is secured the locking lever 38 having a forked end which engages with the stud 39. The stud is fixed to the bolt 41 and in the hub 12 there is provided a hole 42 adapted to accommodate the end of the bolt 41 when the isolating switch has been moved into its full open-circuit position.

The operation of this arrangement is as follows: When the isolating switch is closed (and also the circuit-breaker with which the isolating switch is associated) the parts are in the position shown and the key is trapped into the lock. In order to obtain the key, it is necessary first to rotate the handle 19 in a clockwise direction sufficiently for the shutter 18 to uncover the opening of the hole 17, or, in fact, until the disc 22 is engaged by the lever 29 of the spring-controlled clamping device. This rotation immediately effects the tripping of the circuit-breaker through the link 21, and it is then safe to open the isolating switch, which can be done by inserting an implement in the hole 17 whereby leverage can be applied to rotate the hub 12 until the center line of the hole 17 coincides with the broken line 32. The isolating switch is now fully open and the hole 42 has moved into alignment with the bolt 41. The arrangement is now in a position for the key 36 to be turned to rotate the shaft 37 and thereby to shoot the bolt 41 into the hole 42, thus locking the isolating switch open. When this has been done the key 36 can be withdrawn. It should be noted that the key cannot be turned unless the hole 42 is aligned with the bolt 41, as for all other positions of the hole 42 the bolt 41 just bears against the surface of the hub 12. When the key 36 has been withdrawn it is available for insertion in one of the locks of the chamber doors hereinafter described.

Referring now to Figs. 3 and 4, there is shown a part of a sliding door 43 adapted to

close the front of a chamber having side walls 44. The door 43 may be mounted upon suitable rollers and is slidable to the right. The chamber may contain one or more circuit-breakers or other apparatus. When the door is locked in closed position, the locking lever 45 secured to and operable by the shaft 37 of the lock 35, which is secured externally to the door, is arranged to bear against the plate 47 secured internally of the chamber to one of the walls 44. When the key 36 is inserted in the lock 35 (and the key and lock are so arranged that the key can only be inserted in or withdrawn from the lock when the locking lever thereof is in locked position) the locking lever 45 can be rotated into the position shown by broken lines, in which position, it will be noticed, the top of the plate 47 is just clear of the lower edge of the block 48 on the locking lever 45 and the door can therefore be withdrawn. A roller-cam 49 fixed internally of the chamber to one of the sides 44 is adapted to engage with the cam lever 51 pivoted at 52 to the door. As the door slides out, the inclined surface 53 of the cam lever 51 bears against the roller-cam 49 and causes the lever 51 to rise to the position shown by broken lines, a bracket plate 54 guiding it. The cam lever 51 has secured to it a latch lever 55, adapted, when in raised position, to bear against the inclined surface 56 of the locking lever 45, thus retaining the same in its unlocked position.

It will be obvious from the foregoing that, once the lock is unlocked and the door is moved into open position, the key is positively trapped in this lock until such time as the door has again been shut and the key turned to lock it closed.

In Figs. 5 and 6 a portion of a cover 57 is hinged, as at 58, to one of the side walls 44. On this wall there is fixed a bracket 59 having a projecting cam portion 61 adapted to engage with a cam 62 on the cam lever 63 which is pivoted at 64 to a bracket 65 secured externally to the door 57. When the door is closed and locked the end 66 of the locking lever 45 mounted on the shaft 37 engages against the upturned end 67 of the plate 68 secured to the other wall 44, thus preventing the door from being opened. When the key 36 is inserted in the lock 35, the locking lever 45 can be rotated by means of the key to the position shown by broken lines, when its end 66 is just clear of the upturned end 67 of the plate 68, and the door can, therefore, be swung open. The swinging open of the door causes the cam lever 63 to rotate anti-clockwise about its pivot 64, due to the engagement of the cams 61, 62 and this movement of the cam lever 63 is transmitted to a latch lever or rod 69 carried by brackets 71 on the door causing the end 72 thereof to engage with a cooperating portion 73 on the locking lever to retain the same in its unlocked position. The

compression spring 74 bearing against one of the brackets 71 and against the sleeve 75 secured to the rod 69 is provided for returning the rod to its off position when the door is again closed.

In Fig. 7 there are shown a number of doors 76 hinged to walls 44 and covering the front of a number of chambers arranged side-by-side between the walls. In normal conditions a bar 77, hinged for movement about the pivots 78 by links 79, lies close across the tops of the doors, whereby they are prevented from being opened. A locking bar 81 adapted to pass through the lock-frames 85 of the locks 35 carries at its upper end a forked bracket 82 to which is secured a pin 83 lying in a slot 84 in the bar 77. The bar 81 is normally retained in the position shown in Fig. 7 by means of the locks 35, thus holding the bar 77 in its lower position to prevent the opening of the doors 76. Three such locks are shown here, there being one lock for each isolating switch associated with the circuit breaker in the respective chambers covered by the doors 76. Only when all these locks 35 are unlocked can the handle 86 be operated to raise the locking bar 81 and thereby to raise the bar 77 into the position shown by the broken lines, when it is just clear of the upper ends of the doors 76. So soon as any or all of the doors are open, the bar 77 will lie on the top thereof and will therefore be prevented from moving into its lower position. The locks 35 may be arranged as shown in Figs. 8 and 9. The bar 81 passes through each lock frame 85 and is provided with slots 87 adapted when the locks are locked to be engaged by the cylindrical locking members 88 operable by the square shafts 37. Each member 88 is provided with a slot 89 which is arranged to be aligned with the bar 81 when the key 36 has been inserted in the lock 35 and turned through approximately 60°, thus permitting the bar 81 to be moved, provided that the other locks are unlocked. As soon as all the locks have been unlocked and the bar 81 moved upwardly, the full width of the bar 81 will occupy the slots 89 of the locking members 88 of each of the locks 35 and thereby prevent their respective keys from being turned, which cannot in fact be effected until all the doors 76 have again been closed, whereby the bar 77 and the bar 81 can be moved into their lower positions.

It should be understood that, as it is common for each circuit breaker to be associated with two or more isolating switches, the locks on the doors and the trapping arrangements may be duplicated or triplicated, there being one lock and its associated parts for each isolating switch.

While I have described certain embodiments of my invention, I do not wish to be limited to the particular forms shown and described as it will be apparent that many

modifications therein may be made without departing from the scope of my invention as set forth in the appended claims.

What I claim as new and desire to secure by Letters Patent of the United States, is:

1. In combination, an isolating switch operating mechanism, a key actuated lock for securing said mechanism in open circuit position, a chamber having a door adapted to enclose a main switch in series with the isolating switch, a lock for said door, said mechanism lock and said door lock being constructed to be actuated by the same key and positively to prevent the removal therefrom of said key respectively when the isolating switch mechanism is in closed circuit position and when the chamber door is not closed.

2. In combination, an isolating switch operating mechanism, a key-actuated lock for securing the mechanism in open circuit position, said key being removable from the lock only when the switch is locked in open circuit position, a chamber having a door adapted to enclose a main switch in series with the isolating switch, a lock for securing said door in closed position, said door lock being operable by said key and being constructed to prevent removal of the key when the lock is in unlocked position, and means for positively preventing movement of said door lock to locking position when the door is not closed.

3. In a system comprising an isolating switch and a main switch in series therewith, a rotatable operating member for the isolating switch having an opening therein adapted to receive an actuating rod, a rotatable shutter adapted in one position to extend over said opening and a connection between said shutter and said main switch whereby the latter is tripped open when the shutter is moved from the position covering said opening.

4. A chamber adapted to enclose a switch comprising a door, a key actuated lock thereon, said lock being constructed to permit removal of the key when the lock is in locking position and to prevent removal of the key when the lock is in its unlocked position, and means nonreleasable while the door is not closed for preventing movement of the lock to locking position.

5. A chamber adapted to enclose a switch comprising a door, a key-actuated lock therefor, said lock being constructed to permit the removal of the key when the lock is in locking position and to prevent the removal of the key when the lock is in unlocked position and means automatically operated by movement of the door from its closed position for positively preventing movement of the lock to locking position.

In witness whereof, I have hereunto set my hand this 19th day of February, 1925.

CHARLES W. WOOD.
